(57) CLAIM

The ornamental design for an absorbent article package, as shown and described.

DESCRIPTION

FIG. 1 is a perspective front view of a windowed absorbent article package embodying the new design;

FIG. 2 is a front view of the design shown in FIG. 1;

FIG. 3 is a rear view of the design shown in FIG. 1;

FIG. 4 is a ride side view of the design shown in FIG. 1;

FIG. 5 is a left side view of the design shown in FIG. 1;

FIG. 6 is a top view of the design shown in FIG. 1; and,

FIG. 7 is a bottom view of the design shown in FIG. 1.

Broken lines shown in the figures depict environment subject matter only and form no part of the claimed design.
